UNITED STATES PATENT OFFICE.

ARTHUR C. NOTHSTINE, OF PITTSBURGH, PENNSYLVANIA.

BOTTLE CAP AND STOPPER.

1,168,410.

Specification of Letters Patent. Patented Jan. 18, 1916.

Application filed March 23, 1914. Serial No. 826,560.

To all whom it may concern:

Be it known that I, ARTHUR C. NOTHSTINE, a citizen of the United States, residing at Pittsburgh, in the county of Allegheny and State of Pennsylvania, have invented certain new and useful Improvements in Bottle Caps and Stoppers, of which the following is a specification.

The present invention relates to a combined stopper and cap, which is particularly designed and adapted for use in connection with laboratory reagent bottles.

A further object is to combine a stopper with a bottle cap, in such a manner as to produce an article especially adapted for reagent bottles, irrespective of the size of the bottles.

The accompanying drawings illustrate my invention.

Figure 1 shows a vertical section of the upper part of the bottle, provided with a stopper and cap made in accordance with a preferred form of my invention, and Fig. 2 shows a section taken on the line *a—a* of Fig. 1.

Referring more particularly to the drawings, the bottle 1 is provided with a suitable neck 2 to which is ground a glass stopper 3 in the usual manner. This stopper is provided with a cap 4, which as illustrated may be approximately hemispherical, although if so desired any other form may be adopted.

In Fig. 2 the cap 4 is shown as being circular in cross-section, although obviously it may be of any desired form, instead of being circular. It will be noted that the height of the cap 4 is somewhat greater than the height of the stopper 3, so that the stopper and cap, after being removed from the bottle, may be directly laid upon the bench or work table in the laboratory without danger of contaminating the stopper, or the liquid to be held in the bottle 1. The cap 4 obviously prevents dust and fumes from settling upon the pouring lip 5, which is a disadvantage in bottles of this character, for the reason that it is always desirable to add the material from the bottle 1

to the material being treated or tested, 50 without adding any impurities.

I call attention to the fact that caps have heretofore been placed upon reagent bottles of this character, an ordinary hemispherical cap or cylindrical cap being frequently 55 used for this purpose. This, however, is open to the objection that two steps are necessary for the opening of the bottle, namely the removal of the cap, and thereafter the removal of the stopper, while in accordance 60 with my invention, the cap and stopper will be removed in a single operation. Moreover, as above stated, by making the cap longer than the stopper, I can avoid contaminating 65 the liquid in the bottle 1.

Heretofore it has been necessary to handle the stopper itself, by means of which small quantities of the liquid within the bottle are apt to come in contact with the fingers of the operator, thereby producing discolorations or sores, which is also avoided by means of the combined bottle cap and stopper forming my invention. It will be noted that the lower edge of the hemispherical cap 4, is some distance away from the bottle 1, so that when the stopper sticks in the bottle, as stoppers in reagent bottles frequently do, the lower edge of the cap may be tapped lightly, in order to loosen the stopper. 70 75 80

What I claim is:—

The combination with a glass reagent bottle having a pouring lip, of a glass stopper ground to the neck of said bottle, and a cap integral with said stopper, said cap being 85 of greater height than said stopper, the lower end of said cap being entirely free from contact with the outer surface of said bottle, and spaced therefrom a considerable extent, substantially as, and for the purposes described. 90

In testimony whereof I have affixed my signature in presence of two witnesses.

ARTHUR C. NOTHSTINE.
